UNITED STATES PATENT OFFICE.

FREDERICK LOUIS BRANO, OF NEW YORK, N. Y.

RECEPTACLE FOR TOILET POWDERS.

1,278,841.

Specification of Letters Patent. Patented Sept. 17, 1918.

Application filed February 9, 1916. Serial No. 77,151.

To all whom it may concern:

Be it known that I, FREDERICK LOUIS BRANO, a citizen of the United States, and resident of the borough of Manhattan, city, 5 county, and State of New York, have invented certain new and useful Improvements in Receptacles for Toilet Powders, of which the following is a specification.

The device, the subject of this invention 10 is intended as a holder for toilet powders and has for particular advantages, an automatically operating closure which will keep the receptacle closed at all times.

This closure is so designed and constructed that even during the delivery of the powder from the receptacle the contents of the receptacle is not subjected to the atmosphere or to any dust, dampness or other objectionable influence.

20 The closure is also arranged so that it will deliver certain pre-determined quantities of powder in a well defined and molded shape. It is therefore possible to use this receptacle with the least possible loss of 25 material. All of the advantages and the construction of the device will be fully set forth as the specification progresses.

The following is what I consider the best 30 means of carrying out the invention and the accompanying drawing forms a part of this specification in which:

Figure 1. shows in elevation partly in perspective, a receptacle of my construction.

Fig. 2. shows my device in operable position.

Fig. 3. is a front elevation with the delivery nozzle open.

Fig. 4. is a sectional view of the cylinder.

Fig. 5. is a sectional view of the cylinder 40 the view being taken on the line 5—5 in Fig. 3.

Fig. 6. shows a modification of the operating means.

Fig. 7. shows a modified form of container.

Similar reference numerals indicate like parts in all of the figures where they appear.

It will be noted that in the drawings my receptacle is oblong in shape, that one of 50 the sides is obliquely arranged and for the best operation of my device I prefer the oblong or square shape with a sufficient taper at the center or at one side of the center to produce a delivery chute. The 55 container shown in Figs. 1 and 2 is formed of two parts. The bottom portion is a box

as indicated at 1, the top of which is opened, and over or engaged with the opened top is the upper section 2 of the box. It will of course be understood that the connection 60 between the two sections should be sufficiently tight to prevent the material contained within the receptacle from passing through the joint.

Formed above and integral with the 65 upper portion 2 as a plurality of cup shaped projections 3 and 4 one upon each side wall, and it will be noted that the taper 5 terminates in the cupped projections 3 and 4.

The top of the receptacle is closed except 70 for that portion that extends between the members 3 and 4 and between these members I arranged a cylinder 6 which may by the use of the handle 7 be rotated in the cupped members 3 and 4.

75 In one side of the cylinder 6 I form a recess 8 by depressing the side of the cylinder for a sufficient extent or by cutting away the side and inserting a trough of proper outline and area.

80 Within the cylinder and secured one end to the cylinder and the other end to one of the cupped members is a spring 9. The spring should be a coiled or torsional spring and the action of this spring will tend to 85 rotate the cylinder 6 until the stop 10 impinges upon the adjacent side wall of the upper member 2. When the stop 10 is in the position shown in Fig. 1, the recess 8 will be in communication with the interior 90 of the receptacle and at this time when the receptacle is turned into the operative position as shown in Fig. 2 powder or other material within the receptacle will pass into the recess 8.

95 The spring above referred to may, as shown in Fig. 5, be formed integral with the operating handle 7 and when so formed it will be provided with a projection 11 which may be engaged in a perforation in the 100 cupped member 3. Before engagement however the projection 11 should be rotated in the direction of the return rotation of the cylinder 6, so that when secure the spring will induce the cylinder to return to the position shown in Fig. 1.

I desire to call particular attention to the shape of the recess 8. In cross section this recess 8 is a V shaped trough but the ends of the trough should be rounded and should 110 also be arranged upon an angle so that material received into the trough will drop away

therefrom without difficulty and without breaking the even outline of the material which has been shaped by its reception into the recess 8.

5 This device is particularly well adapted for use with tooth powders and as shown in Fig. 2, an operation of the cylinder 6 will cause the discharge from the receptacle of a pre-determined quantity of powder, a quantity that is determined only by the area of the recess 8.

10 In operating my device the cylinder is allowed to remain in the position shown in Fig. 1 until the receptacle is reversed and 15 then when the cylinder 6 is brought into close proximity with the bristles 12 of a tooth brush the handle 7 may be depressed upon the oblique portion of the receptacle or into the position shown in Fig. 2. This 20 will rotate the cylinder or will pass it through one half of a revolution with the result that the recess 8 in the cylinder will be turned outward and will deposit its contents upon the bristles of the brush. The 25 second discharge of material cannot take place until the cylinder 6 is allowed to return to its original position that as shown in Fig. 1, whereupon and if the container is held in the reverse position, the recess 8 will 30 again become filled with powder to be discharged in the manner previously set forth.

I have stated that a coiled spring is used for the return operation of the cylinder 6. I 35 may however use any torsional spring and in Fig. 6 I have shown a side spring one end of which is secured to the cylinder 6 and the other end of which is received in a slot in one of the cupped shaped members. It will 40 also be noted that the shape of my device may be altered and that other modifications

may be made within the scope of the appended claims without departing from the principle or sacrificing the advantages of the invention.

Having carefully and fully described my 45 invention what I claim and desire to secure by Letters Patent is:

A device for retaining and delivering 50 toilet powders and the like, comprising a container, a plurality of cup-shaped members formed integral with said container, a hollow cylindrical member having a V-shaped recess formed therein, said member being rotatably supported with one of its ends in each said cup-shaped member, a 55 torsional spring within said cylindrical member away from said recess, and adapted to rotate said cylindrical member in one direction, a handle formed integral with one end of said spring, and projecting through 60 and exterior to said cylindrical member for rotating said cylindrical member against the tension of said spring, a hook formed at the other end of said spring, and projecting through and engaging one said cup member, 65 and a stop on said cylindrical member to limit the extent of the influence of said spring, said cylindrical member serving to deliver predetermined quantities of material from said container, and to retain 70 said container continuously closed as herein specified and for the purpose set forth.

Signed at New York city, in the county and State of New York, this 15th day of Dec. 1915, in the presence of two witnesses.

FREDERICK LOUIS BRANO.
